UNITED STATES PATENT OFFICE.

CHARLES A. DAWES, OF ST. LOUIS, MISSOURI.

DELIVERY MECHANISM FOR NEWSPAPER-VENDING MACHINES.

1,004,856.

Specification of Letters Patent.

Patented Oct. 3, 1911.

Application filed November 7, 1910. Serial No. 590,959.

To all whom it may concern:

Be it known that I, CHARLES A. DAWES, a citizen of the United States, and resident of St. Louis, Missouri, have invented certain new and useful Improvements in Delivery Mechanisms for Newspaper - Vending Machines, of which the following is a specification containing a full, clear, and exact description, reference being had to the accompanying drawings, forming a part hereof.

My invention relates to improvements in delivery mechanisms for newspaper vending machines and is particularly directed to improvements in the delivery mechanism shown and described in my U. S. Letters Patent #967112, of August 9, 1910.

The object of the present invention is to generally improve the construction of the delivery mechanism whereby it may be made of a lesser number of parts, hence less expensive to construct and which is equally efficient in its operation as the delivery mechanism in the Letters Patent above referred to.

With the above purposes in view, my invention consists in certain novel features of construction and arrangement of parts as will be hereinafter more fully described, pointed out in the claims and illustrated by the accompanying drawings, in which:

Figure 1 is a front elevation of my improved delivery mechanism illustrating its connection with the coin-controlling mechanism, the machine casing being shown in section; Fig. 2 is a vertical, sectional elevation taken on the line 2—2 of Fig. 1; Fig. 3 is a vertical, sectional elevation illustrating, in detail, the delivery mechanism and is taken approximately on the line 3—3 of Fig. 1; Fig. 4 is a front elevation illustrating the delivery mechanism with the newspaper-engaging devices removed; Fig. 5 is a detail elevation of a portion of one of the supports for the newspaper-engaging devices; Fig. 6 is a detail, sectional elevation taken on the line 6—6 of Fig. 4; Fig. 7 is a sectional plan taken on the line 7—7 of Fig. 6; Fig. 8 is an inverted plan illustrating the follower and the racks; Fig. 9 is a vertical, sectional elevation taken on the line 9—9 of Fig. 3; Fig. 10 is a detail perspective of one of the newspaper-engaging devices; Fig. 11 is a detail, sectional elevation through the coin-controlling mechanism and is taken on the line 11—11 of Fig. 1; and Fig. 12 is a detail elevation illustrating one of the newspaper-

engaging devices in a position after having been released, and in a position to permit downward movement of the follower without contacting therewith.

Referring by numerals to the accompanying drawings: 1 designates the machine casing and 2 the hinged forward wall through which access may be had to the interior of the casing; as shown, the casing has greater width at its base than at its top which is the design of casing I propose to use. As shown, the wall 2 is of a less length than the length of the casing, thereby leaving an opening 3 through which the newspapers are discharged from the machine.

Extending the width of the machine is a sheet metal upright 4, over which there is supported the trap 5 which trap, as shown, extends the full width of the machine and 75 coacts with the upright 4 to close the delivery opening against the insertion of probes or the like for the purpose of unlawfully tampering with the machine to surreptitiously remove the newspapers therefrom. As shown, the portion 6 of the trap 5 is a larger body than the horizontally disposed portion of the trap, hence holding the trap, by gravity, in a position with its margin 7 normally engaging the inner face of 80 the wall 2.

Centrally located within the casing and secured to the bottom and rear wall thereof is the L-shaped frame 8, having the integral inclined portions 9 and 10 to which are secured the members 11 and 12 constituting supports for the newspaper-engaging devices hereinafter more fully described.

Formed integral with the members 11 and 12 are the right-angled portions 13—13, 95 each inner margin of which has formed therein the notches 14 throughout its length and equi-distantly spaced apart. In the member 11 there are a number of perforations 15 which are spaced an equi-distance 100 apart throughout the length of the member 11 and, coincident with the perforations 15 are the perforations 16 in the member 12, the perforations 16 being of greater length than the perforations 15, and disposed approximately vertical. Formed in the member 12 are a number of notches 17 in its upper margin, which notches are spaced an equi-distance apart.

18 designates the body portion of one of 110 the newspaper engaging devices, all of which are constructed of the same confor-

mation and may be stamped from single pieces of sheet metal. Each of the plates is of a length corresponding to the distance between the supporting members 11 and 12.

5 19 designates an integral, right-angled portion projecting beyond the side margins of the plate proper, the end portions of which constitute supports for the plates, and which are journaled in the perforations 15 10 and 16.

Formed in the margin of each plate, adjacent the supporting member 12, is a shoulder 20 arranged for coaction with one of the notches 17 to hold the plate in a substantially vertical position, (the position necessary to support a newspaper in the machine). Each of the extensions 9 and 10 is provided with an integral down-turned extension 21 which are slotted for the support 20 of a movable rack-bar 22. Connecting with the upper end of the rack-bar 22 is a pitman 23, which pitman connects the rack-bar 22 with the bell-crank lever 24, the bell-crank being mounted upon a shaft 25 which 25 is connected with a suitable coin-controlling apparatus, which coin-controlling apparatus is provided with a crank for manually operating the machine in one direction against the pressure of the spring 26, which 30 spring returns the lever and said crank to their normal positions after being manually released.

The coin-controlling mechanism shown is made the subject of an application for Letters Patent filed herewith, hence a detail description is not deemed necessary.

While I have shown one form of coin-controlling mechanism, I do not desire to be understood as limiting myself to the construction of the coin-controlling apparatus shown.

Arranged for movement lengthwise between the members 11 and 12 is a metallic block 27, upon the upper face of which 45 adjacent the member 12 is a boss 28 of sufficient height to engage the lower extremity of the newspaper-engaging devices 18 when said devices are set in positions approximately vertical for the purpose of holding 50 a paper.

By reason of the length of the plates and by reason of the weight of the papers falling over the plates after they have been released from the notches 17, the plates are 55 placed in the positions, as shown in Fig. 12, with their right hand ends in positions above the path of travel of the boss 28, thereby permitting free movement of the boss lengthwise relative the machine when all of 60 the newspaper-engaging devices have been released.

Carried by the block 27 is a pair of crossed arms 29, the left hand ends of which are of some considerable length forming 65 handles for the manipulation of the block

27. Each of the arms is provided with an integral dog 30, arranged to engage in the notches 14, formed in the horizontal portions of the newspaper-engaging device supports, and also to coöperate with the movable rack-bar 22 for the movement of the block 27 carrying the boss 28. The support for the newspapers, to hold them in proper positions over the newspaper-engaging devices 18 consists of pairs of wires 31 70 arranged on either side of the delivery mechanism proper. These wires are arranged substantially parallel with the supporting members 11 and 12 and, as shown, are in a plane slightly above the upper margins of the members 11 and 12, the elevation of the wires 31 over the supports 11 and 12 must be sufficient to hold the newspapers in planes above the members 11 and 12, so that as each newspaper is released it will be 80 moved, by gravity, over the wires 31 and their travel not be obstructed by the members 11 and 12.

In the practical operation of the machine, assuming the parts to be assembled, as 90 shown, and in the position indicated in Fig. 3, and that there be newspapers held in place by the engaging devices which are up-standing, and a coin be supplied to the machine and the crank manipulated, it will be 95 obvious that upon a movement of the crank of the coin-controlling mechanism the shaft 25 will be rotated, thus moving the bell-crank lever 24. The rack-bar 22, through the medium of the pitman 23 and one of the 100 pawls 30, will cause the block 27 to be drawn upwardly thereby causing the boss 28 to engage the right-angled portion 19 of the newspaper-engaging device and lift the entire engaging device bodily a sufficient elevation 105 to free the shoulder 20 from the notch 17, thereby permitting the engaging device to fall, by reason of its weight and the weight of the newspaper held thereon, to a position approximately parallel with the supporting 110 members 11 and 12, the other of the pawls 30 serving to hold the block 27 between operations of the rack bar 22.

The operation just described releases a newspaper which slides by gravity over the 115 rods 31, trips the trap 5 and rests upon the bottom of the casing where, by reason of the action of the weighted end 6 of the trap, the paper will be moved outwardly toward the opening 3, so that it may be readily accessible.

I claim:

1. In a delivery mechanism for vending machines, the combination with an inclined article-supporting means, of a pair of supports, article-engaging devices pivotally carried by said supports, there being notches in said supports for holding said devices in positions to engage articles on said supporting means, and means for lifting the arti- 125 130

cle-engaging devices bodily to release them from said notches so that said devices may fall beneath the article-supporting means.

2. In a delivery mechanism for newspaper per vending machines, the combination with an inclined newspaper-supporting means, of inclined, fixed rack bars, newspaper-engaging devices pivotally supported over said fixed rack bars, means for holding said newspaper-engaging devices to project in planes above the newspaper-supporting means, a movable rack bar, dogs operated by said movable rack bar and held by said fixed rack bars, and means, carried by said dogs, for elevating the newspaper-engaging devices to release them to fall in a plane beneath the inclined newspaper-supporting means.
3. In a delivery mechanism for newspaper per vending machines, the combination with an inclined newspaper-supporting means, of newspaper-engaging devices, supports, for the newspaper-engaging devices, having rack bars and notches in the margin of one of said supports, a movable rack bar, dogs movable by said movable rack bar, and means, carried by said dogs, for lifting said

newspaper-engaging devices out of said notches to release them to fall beneath the newspaper-supporting means.

4. In a delivery mechanism for vending machines, the combination with a fixed inclined article-supporting means, of a plurality of article-engaging devices, a support for the article-engaging devices beneath said article-supporting means, a connection between each article-engaging device and said support, whereby each device may swing in the path and direction of travel of a released article, means carried by each device and means carried by said support for holding said devices in position to engage the articles and hold them in place on said supporting means, and a movable means for successively engaging said devices to release them from said support, for the purposes stated.

In testimony whereof, I have signed my name to this specification, in presence of two subscribing witnesses.

CHARLES A. DAWES.
